UNITED STATES PATENT OFFICE.

DANIEL FREDRICK McGOVERN, OF MONTPELIER, VERMONT.

POLISHING-WHEEL.

REISSUED

1,296,985.

Specification of Letters Patent. Patented Mar. 11, 1919.

Application filed November 26, 1918. Serial No. 264,230.

To all whom it may concern:

Be it known that I, DANIEL F. McGOVERN, a citizen of the United States, residing at Montpelier, county of Washington, 5 State of Vermont, have invented certain new and useful Improvements in Polishing-Wheels, of which the following is a specification.

This invention relates to polishing wheels, 10 and particularly to a polishing or "ironing" wheel having scroll-shaped flanges between which abrasive is introduced and by which it is worked against the surface, usually granite, marble or other stone being polished.

In polishing stone, the process usually followed is to first point and build up the rough stone, after which the stone is smoothed or dressed, and is ready for the 20 buffing or finishing step. For the first step an abrasive consisting of hard chilled-iron pellets or shot mixed with sand and wet with water is usually employed; for the second, the abrasive is usually comminuted 25 carbolon, emery powder or similar finely divided substance; while for the third, a reversible felt buffer is used.

My polishing wheel is particularly intended for use in carrying out the first 30 step of the usual polishing process, as distinguished from the second, and involves certain characteristic differences, owing to the difference in the abrasive material used in these steps.

The tendency of the heavy abrasive used in the roughing step is to clog the channels separating the flanges of the scroll, thus causing an unequal distribution of the abrasive, with resultant loss in efficiency. 40 Moreover, the tendency of the abrasive is to be thrown from under the wheel by the centrifugal force developed as the wheel rapidly rotates, obstructs the even and progressive feed of the abrasive toward the 45 center of the wheel. Certain difficulties are also experienced in securing a proper feeding-in of the abrasive, in preventing it from spilling out, and in securing a free working of the material between the flanges.

The object of my invention, generally stated, is to provide a polishing wheel in which the foregoing difficulties are overcome. This object, and certain other features of advantage which will appear more 5 particularly hereinafter, are secured in the

polishing wheel of the present invention. The construction and operation of my invention is disclosed in the following specification, and illustrated in the accompanying drawings, throughout which like reference characters are correspondingly employed.

In the drawings:

Figure 1 is a bottom view of a polishing wheel in accordance with my invention, and Fig. 2 is a side view thereof.

The polishing wheel selected as an illustrative embodiment of my invention has a lateral intake for the abrasive, as distinguished from those wheels in which the abrasive is fed in at the top of the wheel.

I have indicated at 1 a plate or disk forming the frame or body of the polishing wheel and having a central mud-discharge opening 2 and lugs 3 to receive the driving shaft.

My invention consists in the construction and arrangement of the scroll-shaped flanges between which the abrasive works.

According to the present invention, as illustrated herein, the flanges are disposed as double scrolls of progressively increasing length from the center outward and extending circularly about the wheel, as designated by the reference characters 4, 5, 6, 7 and 8 and 4¹, 5¹, 6¹, 7¹, and 8¹, respectively.

Each flange is of substantially segmental form, and is preferably sharpened at its forward end, as indicated at a, to provide a runner. The curvature is such that the respective ends of corresponding flanges are positioned at substantially the same distance from the center of the wheel, and with the exception of flanges 5 and 5¹, the forward ends all terminating in substantially the same plane, indicated at P, Fig. 1. The rear ends of flanges 4 and 4¹ are extended somewhat and overlap the adjacent forward ends of flanges 6 and 6¹, providing chokers 40 and 40¹ overlapping the lateral intake openings for the abrasive and adapted to prevent the abrasive from spilling from the channels, without however impeding free intake of the abrasive. The forward ends of the flanges 5 and 5¹ terminate short of the indicated plane P and are positioned closer to the flanges 4 and 4¹, so that the intake channels for the abrasive are relatively narrow at the periphery of the disk and progressively increase in width as they approach the center. This arrangement also

distributes the balance of the wheel somewhat toward its periphery. The segmental flanges thus provide varied intake openings with overlapping chokers 50 and 50¹ adapted to catch and feed in the abrasive, while preventing the abrasive spilling out as the wheel rotates. Inasmuch as the flanges 5, 5¹, 6, 6¹, 7, 7¹, and 8, 8¹, do not overlap each other, no obstruction is offered to the free working of the abrasive between the flanges.

Various modifications in the form and construction of my device may obviously be made, all without departing from the spirit of my invention, if within the limits of the appended claims.

What I therefore claim and desire to secure by Letters Patent is:

1. A polishing wheel comprising a plate having on its working face duplicate sets of symmetrically arranged segmental flanges disposed on opposite sides of a plane passing transversely across the plate, the rear end of the outermost flange of each set extending beyond said plane and overlapping the forward end of the next inner flange of the opposite set and constituting a

choker effective to prevent the abrasive spilling out.

2. A polishing wheel comprising a plate having on its working face duplicate sets of symmetrically arranged segmental flanges disposed on opposite sides of a plane passing transversely across the plate, the rear end of the outermost flange of each set extending beyond said plane and overlapping the forward end of the next inner flange of the opposite set and constituting a choker effective to prevent the abrasive spilling out, and the forward end of that flange of each set of flanges which lies between the said next inner flange and the said choker flange of its set terminating short of the said plane and providing with the forward ends of the choker flanges relatively staggered abrasive intake openings at opposite edges of the plate.

In testimony whereof I affix my signature in presence of two witnesses.

DANIEL FREDRICK McGOVERN.
